DESIGN FOR A TOY GOOSE

George J. Provol, Winnetka, Ill.

Application June 24, 1946, Serial No. 130,970

Term of patent 14 years

(Cl. D34—15)

To all whom it may concern:

Be it known that I, George J. Provol, a citizen of the United States, residing at Winnetka, in the county of Cook and State of Illinois, have invented a new, original, and ornamental Design for a Toy Goose, of which the following is a specification, reference being had to the accompanying drawing, forming a part thereof.

Fig. 1 is a side elevational view of a toy goose showing my new design;

Fig. 2 is a front elevational view of the toy goose shown in Fig. 1 with one wing broken away for convenience of illustration; and

Fig. 3 is a plan view of the toy goose shown in Fig. 1 with part of a wing broken away for convenience in illustration.

I claim:

The ornamental design for a toy goose, substantially as shown and described.

GEORGE J. PROVOL.
